UNITED STATES PATENT OFFICE.

AMBROSE B. RAMEY, OF CANTRIL, IOWA.

SPRING-BED.

SPECIFICATION forming part of Letters Patent No. 251,946, dated January 3, 1882.

Application filed September 28, 1881. (No model.)

To all whom it may concern:

Be it known that I, AMBROSE B. RAMEY, of Cantril, in the county of Van Buren and State of Iowa, have invented a new and useful Improvement in Spring-Beds, of which the following is a specification, reference being had to the accompanying drawings.

The invention relates to an improvement in beds; and it consists in a novel construction and arrangement of the parts of the bed, whereby the same may be given the desirable qualities of strength, durability, cheapness, and spring, with the consumption of a minimum quantity of material and labor.

The details of construction will fully appear hereinafter.

Referring to the accompanying drawings, Figure 1 is a central vertical longitudinal section of the bed. Fig. 2 is a central transverse section, and Fig. 3 is a top view, of same.

A B indicate the head and foot boards, which are of usual construction and connected by the sides C, in which are formed the recesses a b, the former being on each side of the transverse center of the bed and of proper size to snugly receive the slats D, while the recesses b are at the extreme ends of the bed and elevated above the recesses a.

In the recesses b are placed the ends E of the spring bed-bottom, which consists of the said ends, the wires d, which connect them, and the slats e, carrying the springs f. The wires d extend the whole length of the bed, and their

ends pass through and are secured on the outer edge of the ends E. 35

Upon each side of the transverse center of the wires d are secured the slats e at points corresponding with the position of the slats D. Upon the under surface of the slats e are supplied the helical springs f, which are 40 preferably affixed to the slats e and have their lower ends resting upon the slats D.

It will be observed that although I employ only two rows of springs and but four slats I produce a bed-bottom which at all points has 45 the necessary spring, and is light, strong, and durable.

What I claim as my invention, and desire to secure by Letters Patent, is—

The spring-bed herein described, consisting 50 of the head and foot boards connected by the sides C, having recesses a b, the latter being at the extreme ends of the bed and elevated above the former, the slats D, set in the recesses a, the ends E, placed in the recesses b 55 and connected by the wires d, and the slats e, carrying the springs f, substantially as set forth.

In testimony that I claim the foregoing improvement in spring beds as above described 60 I have hereunto set my hand this 1st day of September, 1881.

AMBROSE B. RAMEY.
